CLAIM

The ornamental design for a mule as shown and described.

DESCRIPTION

FIG. 1 is a front view of a mule showing my new design; FIG. 2 is a back view thereof;

FIG. 3 is a perspective view thereof;

FIG. 4 is a right side view thereof;

FIG. 5 is a left side view thereof;

FIG. 6 is a top view thereof; and

FIG. 7 is a bottom view thereof.

FIG. 8 is a right side view of an alternative embodiment;

FIG. 9 is a left side view thereof;

FIG. 10 is a bottom view thereof;

FIG. 11 is a back view thereof;

FIG. 12 is a perspective view thereof;

FIG. 13 is a top view thereof; and,

FIG. 14 is a front view thereof.

The smaller evenly spaced lines on the mule upper depict stitching, which forms no part of the claimed design. The broken lines showing the sole of the mule form no part of the claimed design.
